UNITED STATES PATENT OFFICE.

WILLIAM BROWN, OF NEWBURYPORT, MASSACHUSETTS.

IMPROVEMENT IN LAMPS.

Specification forming part of Letters Patent No. 124,249, dated March 5, 1872.

Specification describing a new and useful Improvement in Lamps, invented by WILLIAM BROWN, of Newburyport, in the county of Essex and State of Massachusetts.

Figure 1 is a detail vertical section of my improved lamp arranged as a chandelier, part being broken away, and indicating in dotted lines the changes necessary to adapt it for use as a stand or bracket lamp. Fig. 2 is a horizontal section of the same, taken through the line *x x* of Fig. 1. Fig. 3 is a detail view of a stand for supporting the lamp.

Similar letters of reference indicate corresponding parts.

My invention has for its object to furnish an improved lamp which shall be simple in construction, convenient in use, reliable in operation, and entirely safe from explosion; and it consists in the construction and combination of various parts, as hereinafter more fully described.

A is the reservoir in which the oil is placed, and which may be made of glass or metal, or glass and metal, as may be desired. The reservoir is filled through an opening in its bottom, which opening is closed with a screw-cap, *B*. The cap *B* is made with a hole through it, which is closed with a valve, *C*. The valve *C* is held to its seat by a coiled spring, *D*, one end of which is attached to the valve *C*, and its other end is attached to a loop, *E*, which is secured to the said cap *B*. The stem *F* of the valve *C* passes out through an opening in the cap *B*, and has a bottom, knob, or foot formed upon its outer end, which rests upon the bottom of the fountain or receiver *G*, so that the weight of the reservoir bearing upon the said valve-stem may hold the valve *C* away from its seat and allow the oil to flow out freely. To the outer side of the cap *B*, around the opening in said cap, is attached a wire-gauze or finely-perforated sheet-metal cap, *H*, which prevents the possibility of flame entering the reservoir *A*. By this construction, should the lamp be overturned or dropped from the receiver *G*, the valve *C* will be closed by the spring *D* as soon as the valve-stem *F* is released from the weight, so that not a drop of oil can escape, however much the reservoir may be rolled about. *I* is a ring-partition, placed in the bottom of the receiver *G*, made of finely-

perforated sheet metal. The partition *I* thus forms a cavity to receive the valve-stem *F*, and the shoulders of said partition should be of such a height that, when the valve-stem *F* has been pushed inward a sufficient distance to open the valve *C*, the cap *B* or the bottom of the reservoir *A* may rest upon the said partition, as shown in Fig. 1, and thus relieve the spring *D* from having to support the entire weight of the reservoir *A* and its contents. The partition *I* thus forms a ring-chamber around the outer part of the bottom of the receiver *G*, which said chamber is filled with fine sand, *J*, or other suitable material, through which the oil filters as it passes to the burner or burners. *K* are pipes, leading from the receiver *G* to the burners, and the inner ends of which are closed with a wire-gauze or finely-perforated sheet-metal partition, *L*, which prevents the sand *J* from escaping through the said pipes *K*, and at the same time prevents the possibility of flame entering the receiver *G*, even should an explosion occur at the burners. To the outer ends of the pipes *K* are attached receptacles *M*, which receive the oil from the pipes *K*, and the wicks by which the oil is conveyed to the burners, which are screwed into the upper ends of the receptacle *M* in the same manner as they are ordinarily screwed into a lamp-collar. In the case of a lamp-chandelier, the arms or frame *N* are attached to the receiver *G*, as shown in full lines in Fig. 1. In the case of a bracket or stand lamp, lugs *O* are attached to the receiver *G* and reservoir *A* to receive the pivot *P*, as shown in dotted lines in Fig. 1, so that the lamp may be turned from side to side, to throw the light as may be required. The pivot *P* may be secured to the wall permanently, or it may have a hole through its base to receive the standard *Q* of the stand, in which case it is secured in place by a set-screw, *R*, so that it may be turned from side to side, or moved up and down, as may be desired. *S* is the base or foot of the stand, which may have screw-holes formed in it, so that, by reversing the position of the pivot *P* upon the standard *Q*, the base or foot *S* may be screwed to the ceiling, enabling the lamp to be used as a hanging lamp. *T* is a wire or arm, attached to the receiver *G*, and curving upward and outward over the burner, to sup-

port a heat and smoke protector, and which thus turns with the lamp so as to be always over the burner.

The pipes K may be made of any desired length, so that when the lamp is used on railroad cars the reservoir A and receiver G may be placed at any desired distance from the burner, or even outside of the cars. The receiver G should be screwed into or otherwise detachably attached to the ring or base of the arms or frame N, so that the receiver and burners may be taken down when required for trimming the wicks or for other purposes.

Having thus described my invention, I claim as new and desire to secure by Letters Patent—

1. The combination of the stand P Q R S,

constructed as described, with the reservoir, receiver G, pipe or pipes K, receptacle or receptacles M, substantially as herein shown and described, to adapt the lamp for use as a standing or hanging lamp, as set forth.

2. The combination of the perforated guard H, perforated ring-partition I, and perforated guard L with the reservoir A B C D E F, receiver G, pipe or pipes K, to which the receptacle or receptacles M are attached, substantially as herein shown and described, and for the purpose set forth.

WILLIAM BROWN.
